UNITED STATES PATENT OFFICE

GRANT SIPP, OF PATERSON, NEW JERSEY, ASSIGNOR TO SIPP EASTWOOD CORPORATION, OF PATERSON, NEW JERSEY, A CORPORATION OF NEW JERSEY

LUBRICATING SYSTEM FOR QUILLING MACHINES

Original application filed December 2, 1927, Serial No. 237,303. Divided and this application filed October 3, 1929. Serial No. 397,098.

The present application is a division of my application for patent for quilling machines Serial No. 237,303, now Patent No. 1,744,060, Jan. 21, 1930.

5 The object of this invention is to provide in a yarn-winding machine, as a quilling machine, for the adequate lubrication of a moving system of parts including a winding unit and its driving means, the construction being preferably such as to avoid escape of the lubricant to such exterior portions or surfaces of the machine as there is occasion or possibility for the material being wound or the attendant's hands to touch.

15 The drawings show sufficient of the quilling machine disclosed in my aforesaid application to illustrate the present invention,

Fig. 1 being a fragmentary plan, with the cover of the housing removed;

20 Fig. 2 a longitudinal vertical section substantially central of the machine;

25 Figs. 3, 4 and 5 transverse sections on lines 3—3, 4—4 and 5—5, respectively, of Fig. 1; and

Fig. 6 shows in plan, partly in section, a detail of Fig. 5.

It will be understood that the present invention is not necessarily limited to the particular machine which is shown and described herein by way of example.

30 1 is an elongated housing open only at the top (except where certain parts to be indicated protrude) and having a removable cover 2 partially shown by dotted lines in Fig. 2. It may have all around a trough-like flange or lip 3 to catch and confine such oil as may work its way from the housing.

35 The bottom of the housing has upstanding therefrom a continuous wall 5 forming (Fig. 3) an elongated well 6 open at the top, and at both sides of this well a receiver 7 is formed whose bottom slopes toward one end of the housing, where it is suddenly depressed to form a sump, as at 8. The well 6 is kept supplied with oil as I shall explain later.

40 The main horizontal shaft 10 is journaled in a bearing 9 at one end of the housing and it and two rock-shafts 11, one each side of

and in the same horizontal plane as shaft 10, are journaled in a series of spaced bridge-members, to wit, left-and right-hand bridge-members 13 and 15 and intermediate bridge-members 14 (only one being shown), of 55 which the bridge-member 15 differs from the other bridge-members in that it affords bearings whose centers are below the axes of the shafts 10 and 11 and for this purpose it has a pair of spaced depending webs 15a 60 (Fig. 2).

The main shaft may be driven by a belt on the pulley 32 thereon and the rock-shafts are made to rock (in synchrony by having fixed thereon intermeshing toothed segments 65 17) from a lever 21, fulcrumed in the depending webs 15a of bracket 15, through a link 20 pivotally connecting said lever with an arm 18 fixed on one of the rock-shafts, lever 21 having a roller 23 running in a 70 groove 24a of a cam 24 journaled between said webs; this cam is peripherally toothed and meshing with it is a pinion 25 formed with a gear 26 and journaled between said webs, the gear being in mesh with a pinion 75 27 fixed on the main shaft.

Shaft 10 has fixed thereon spiral gears 33 for driving the winding units.

For the present purposes it is unnecessary to describe each winding unit or mechanism 80 for building the wound package (A, Fig. 1) with more particularity than as follows:

Each such unit includes a spindle 35 and a thread-guide 36, the former rotating and the latter in the present example both reciprocating and progressing relatively to the former on the rod 37 and having a fork 36a engaged in the peripheral groove of a nut 38 screwed on a reciprocated threaded traverse-bar 39 and having a friction-wheel 38a to engage 85 peripherally the conical end of the wound package A being formed, so that as, in the reciprocation of the nut with the traverse-bar, the friction-wheel occasionally encounters the package and the nut is turned 90 and fed along the threading of the bar, the thread-guide is both reciprocated and occasionally made to progress, all in a manner well known in this art. The spindle, which is journaled in the opposite side walls of 100

housing 1 and protrudes from one of them, has a spiral gear 40 thereon normally fixed thereto and meshing with one of the gears 33. The traverse-bar 39 is supported in that one of said walls of the housing from which the spindle protrudes and by a link 46 (Fig. 3) it is pivotally connected with a crank 47 on one of the rock-shafts 11, normally fixed thereto. Thus when the shafts 10 and 11 are in motion, as described, the spindle is rotated from shaft 10 and the thread-guide reciprocated from a shaft 11 so that the building of the package will proceed as indicated.

The gears 40 of all the winding units dip 15 into a body of oil B (in well 6) from which it is transmitted, by their rotation and consequent ejection action and largely by spraying, to the various bearings, as of the shafts 10 and 11, the spindles and the rods 39, the 20 thus-ejected oil being of course confined in the housing. The level of the oil is maintained such that said gears 40 dip into the oil at constant depth at any speed of the machine by forming the well with an open 25 top and providing, exterior of the well, a lubricant receiver, 7 (here formed all around the well and including the depression 8), arranged to receive substantially all vagrant lubricant discharged from the well, and by 30 also providing means (as will appear) which returns the oil from the receiver to the well at a faster rate than it is ejected from the well by said gears.

The means last mentioned here consists of 35 an oil-conductor 58 in the form of an inclined chute secured by its bracket 59 to the inner web 15a of bridge-member 15 and having its upper edge formed to the same profile as that of and wiping against the inner face 40 of cam 24, its inner end overhanging well 6. The cam 24, by dipping into the oil in the receiver (where it is preferably deepened, as at 8, in order to immerse this cam at adequate depths), in its rotation and by adhesion of the oil thereto acts as an elevator, 45 carrying the oil up and over to the chute 58, by which it is wiped off the adjoining face of the cam (and which acts as a wiper as well as a chute) and is delivered to the well 6, the rate of return of the oil to the well by 50 this simple means being found in practice considerably to exceed that of its ejection therefrom.

By "vagrant oil discharged from the well" 55 I mean to include what overflows the well and is ejected by the gears 40 and does not remain adhering to any surface within the housing.

Of course by providing an upstanding wall, 5, to form the well I bring, as it were, the level of the oil therein up to the gears 40.

Having thus fully described my invention what I claim is:

60 The combination, with a supporting struc-

ture including a bottom wall, an elongated open-top lubricant well upstanding from said bottom wall and means, upstanding from said bottom wall and spaced from the well at both sides thereof, to form with said bottom wall a housing, said wall and means forming a sump at and exterior of one end portion of the well and said wall having its upper surface inclined both sides of the well toward the sump, of a moving system of parts carried by said structure within the housing and including winding units arranged in a series extending lengthwise of the well and an elongated driving member therefor also extending lengthwise of the well, said member and each unit having coactive means to transmit motion from the former to the latter dipping into the lubricant in the well, and means to return to the well from the sump lubricant ejected from the well by said coactive means and draining to the sump down said inclined surface.

In testimony whereof I affix my signature.

GRANT SIPP.
